PLATE COOLING AND FINISHING MACHINE.

1,389,844.

Specification of Letters Patent.

Patented Sept. 6, 1921.

Application filed July 14, 1919. Serial No. 310,663.

To all whom it may concern:

Be it known that I, OSCAR ROESEN, a citizen of the United States, residing at New York city, county of Kings, and State of New York, have invented certain new and useful Improvements in Plate Cooling and Finishing Machines, fully described and represented in the following specification and the accompanying drawings, forming a part 10 of the same.

This invention relates to certain improvements in machines for treating stereotype and similar printing plates.

It is the especial object of the invention to 15 provide a construction in which a finished stereotype or similar plate may be supported at a point or points intermediate its straight edges and brought into cooling relation with a cooling bath while thus supported. It is 20 a further object of the invention to produce a construction in which a plate thus supported is cooled by rotating it through a cooling bath.

It is a further object of the invention to 25 provide such a cooling device in combination with a finishing mechanism in which the plate may be automatically delivered from the finishing mechanism to the cooling carrier and in which the carrier is stopped to 30 hold the plate in the bath during the period required for forwarding a second plate to the carrier, and in which the cooled and finished plate is automatically delivered from the cooling carrier.

It is a further object of the invention to 35 provide supporting devices by which the plate is supported intermediate its straight edges during its movement to and from the finishing mechanism when used and to, on 40 and from the rotary cooling carrier.

It is a further object of the invention to 45 provide automatic means for forwarding a finished plate from the finishing mechanism to cooling position and from cooling position to a suitable delivery in which the forward- 45 ing mechanism is set in motion by an incoming plate which is being forwarded to

the finishing mechanism, thus requiring no attention on the part of the operator for forwarding a finished plate to the cooling carrier or delivering a cooled plate therefrom.

With these and other objects not specifically referred to in view, the invention consists in certain novel parts and combinations which will be hereinafter described in connection with the accompanying drawings, which show the preferred embodiment of the invention and in which—

Figure 1 is a central vertical section partly broken away of the improved cooling device 60 shown in combination with a plate finishing mechanism.

Fig. 2 is a central section partly broken away showing certain of the parts illustrated in Fig. 1, the parts being shown in a different position.

Fig. 3 is a vertical cross section of the construction shown in Fig. 1, the section being taken on line 3—3 of that figure.

Fig. 4 is a detail view partly broken away 70 and partly in section showing on an enlarged scale the mechanism for starting the machine.

Fig. 5 is an end view partly in section taken on the line 5—5 of Fig. 1, showing in 75 end elevation the mechanism shown in Fig. 4.

Fig. 6 is a detail plan view of the construction shown in Fig. 5.

Fig. 7 is a sectional detail on an enlarged scale showing the method of mounting and 80 driving the rotary cooling carrier.

Fig. 8 is a vertical cross section of the rotary cooling carrier and tank, the section being taken on line 8—8 of Fig. 1.

Fig. 9 is a detail sectional view of the plate 85 feeding mechanism used for feeding the plates out of the finishing mechanism and to and from the cooling carrier, the section being taken on line 9—9 of Fig. 1; and

Fig. 10 is a detail sectional view showing 90 the feeding pawl and its spring, the section being taken on line 10—10 of Fig. 9.

Referring now to the drawings, the invention has been illustrated as embodied in

a combined machine for both finishing and cooling the plates. It will be understood, however, that if desired, the cooler may be used alone or in conjunction with a finishing mechanism of a type other than that here shown. The invention will, however, be described in connection with the finishing machine shown, and for convenience the finishing of the plate will be described first.

10 Whatever the type of finisher employed, however, preferably the hot plate will be supported at points intermediate its straight edges, while it is being directed into the finishing mechanism, and while it is being 15 moved from the finishing mechanism to the cooler, and while it is on the cooler.

In the particular construction illustrated, there is provided a plate support on which the hot plate is placed by the operator. This 20 support is of such character as to support the plate on its inner periphery so that the weight of the plate is taken off its straight edges. In the particular construction illustrated, there is provided a block 1, suitably 25 supported in frames 2, of any usual or suitable construction, which support the various parts of the machine. This block 1 forms a support for a head or plate 3 in which are mounted at one end a plurality of supports in the form of bars 4. These supporting bars are provided in sufficient numbers to form an effective support for the plate, four such bars being shown. These bars 4 at their other end are mounted in a similar 30 plate or head 5, which is mounted in any suitable manner as by being secured (see Fig. 7) through screws 6 to the bearing 7 of the finishing knife carrier bar 8, hereinafter referred to. The head 5 is as shown, at the 35 delivery end of the finisher, and the bars extend from the head 3 through the finisher thus providing a continuous support for the plate to and through the finishing mechanism, this support being located intermediate the straight edges of the plates and acting 40 to keep the weight of the plates off such edges.

The particular character of the finishing mechanism may be widely varied, but in the 50 best constructions the plate will be fed into the finisher by hand, the finisher then started to finish the plate and the plate automatically removed from the finisher to the cooler. And, furthermore, in the best type of the 55 machine the finisher will be such that the inside of the plate is shaved or finished by rotating the plate around a fixed knife. In the particular construction illustrated, the finisher is in the form of a shell 9 into which 60 the plate is fed, and in which it is clamped so that it can be rotated with the shell to effect the finishing operation. Various clamping means may be employed for locking the plate in the shell. In the particular 65 construction illustrated, there is provided

a stationary ledge or abutment 10 and a movable abutment 11, the abutment 11 being automatically moved into locking and unlocking position, as hereinafter referred to. The inside of the plate is shaved or finished 70 by a stationary knife 12, this knife being mounted on the fixed shaft 8, before referred to, this shaft taking bearing in the bearings 7 in the frame of the machine.

In the best constructions, means are provided for preventing a plate from being forwarded to the finishing mechanism during the operation of the latter, and for preventing the finishing mechanism from acting while the plate is being moved into or 75 out of the finisher. And in the best constructions, these means will be such as to be controlled by the entering plate. While this may be effected in various ways, in the particular construction illustrated, there is 80 provided a roll 13. (see Figs. 1, 2 and 4) which is normally in the path of the entering plate and with which the plate contacts, as shown in Fig. 1. This roll is carried on a rock arm 14 which rocks around 85 a continuously driven shaft 15. This rock arm at its other end carries a bearing 16 (see Fig. 5) in which is a short vertical shaft 17, which at its upper end carries a miter 18 which meshes with a miter 19 on the shaft 90 15, before referred to. The shaft 17 carries a worm 20, which is arranged when the rock arm 14 is operated by the plate, to be swung into engagement with a sector 21 on a short shaft 22 supported in brackets 23, suitably 95 secured to the frame of the machine. The shaft 22 carries fast thereon a lever arm 24 which is connected to one end of an actuator rod 25. The other end of this rod 25 carries a block 26 in which is adjustably 100 supported at one end a rod 27, the other end of this rod carrying a yoke 28 (see Fig. 3) in which is mounted a stud 29, which carries a pair of large gears 30 and a small gear 31. The gears 30 mesh with a sliding rack 110 32 which carries a pair of plate forwarding pawls 33 which are normally pressed into forwarding position by springs 33', and the small gear 31 meshes with a stationary rack 34 suitably supported in any suitable manner, as by the cutter bar, before referred to, and the bearing 7 of the cutter bar shaft. Two gears 30 are employed spaced to lie on 115 each side of the rack 34, thus acting to steady the parts. The gears 30, 31, act as a 120 multiplying device so that a small movement of the sector 21, before referred to, will move the rack bar 32 a sufficient distance to move a plate from the finisher and deliver it to the cooler and remove a plate 125 from the cooler to the final delivery. The forwarding movement of the forwarding rack 32 is stopped by the sector 21 running off the driving worm 20, the parts then operating idly.

The mechanism whereby the machine is locked while a plate is entering or is being delivered from the finisher, and by which, when the plate is correctly positioned

5 in the finisher the machine may be started, is operated from the shaft 22 and is controlled by the entering plate.

In the particular construction illustrated, there is provided an arm 35 loose on the 10 shaft 22 (see Fig. 1). This arm supports one end of a rod 36 having a spring 37, and the other end of this rod 36 is connected to a lever 38 pivoted at 39, this lever connecting through a rod 40 with a latch plate 15 41, having a latching nose 42, this latch plate being loose on a transverse clutch shaft 43. The spring 37 normally tends to throw the nose 42 under a stop 44' on a clutch lever 44 pivoted at 45 (see Fig. 3) in the frame 20 of the machine, and acting to hold the lever against a downward movement and hold the lever so that it cannot be moved to cause an operation of the carrier until the nose 42 has been moved out of its relation with 25 stop 44'. Fast on the shaft 22 is a striker block 46, which, when in the position shown in Fig. 1, forces the spring rod 36 to the right and frees the nose 42 from the lever 44 so that the operator may start the machine.

The plate forwarding rack 32, before referred to, is returned to position after forwarding the plate through a spring 47 secured to the frame and to a projection 47' 35 on the sector shaft 22, before referred to, and which operates through the lever 24 to pull back the rack. The roll 13 is rocked by the movement of a plate against the action of a spring rod 48 of usual construction 40 secured to the rock arm 14. When a plate has passed beyond the roll the spring rocks the arm 14 and thus swings the worm 20 away from the sector 21. The latter being now free the spring 47 can act to pull 45 the lever 24 backwardly and cause the backward or return movement of the rod 25 and the parts operated thereby. With this construction the machine cannot be started until a plate is fully in position in the finisher.

50 In the best constructions, means will be provided for preventing a plate from operating the actuator roll 13 while the machine is operating, so as to prevent the roll 13 from setting into operation the mechanism 55 described, and which might cause injury to parts of the machine. While this construction may be varied, in the particular construction illustrated, there is provided a pin 49 in advance of the roll 13 (see Figs. 3 60 and 4) which is actuated to rise in the path of an incoming plate and stop the advance of a plate while the machine is in operation and before it gets to the roll 13. This pin is actuated in the construction illustrated, from an arm 50 pivoted on a shaft 51

which at its other end carries a lever 52 connected to a link 53 in turn connected to a lever 54 having a roll 55 actuated from a groove 56 in a clutch hub 57 on shaft 43, before referred to.

70

The parts being in the position shown in Fig. 1, the operator moves the long lever 58 downwardly, which movement through lever 44 shifts the clutch hub 57 having the clutch face 57' to the left in Fig. 3 which 75 then engages the co-operating clutch member 57' thereby rotating the shaft 43 and causes a worm 59 mounted thereon to revolve and through it to turn the shell 9, before referred to, through a worm gear 60 on the 80 shell with which worm 59 engages. When the clutch hub 57 is thus moved into clutching engagement the lever 54 is actuated and causes the pin 49 to rise into the path of a plate. This pin 49 will, furthermore, act 85 to lift a plate which might be in contact with the roll 13 off the roll if such plate should happen to be in that position when the machine was started.

The movable rib or ledge 11, before referred to, is formed on its rear or outer side with a beveled portion 61 which bears against a movable wedge 62, which in turn contacts with a cam piece 63 fixed on the frame of the machine. This ledge or rib 95 11 is normally forced upwardly into plate locking position by a spring 62', and acts to clamp the plate in the cylinder against the fixed rib or ledge 10. When the shell 9 is in position to receive a plate the ledge 100 is depressed sufficiently to form a clearance so that a plate may enter the shell, but as soon as the cylinder commences to rotate the wedge 62 passes by the cam 63 and the spring acts to lift the rib or ledge and clamp 105 the plate in the carrier. When the shell has made a revolution and the finished plate is ready to be moved the wedge 62 rides up on cam 63 and unlocks the plate which then settles on and is supported by the supporting bars, before referred to, the plate when released from the clamp being supported 110 only by these bars.

In constructions embodying the invention, cooling devices will be employed for cooling 115 the finished plate, and these devices will be of such character that the plate is supported intermediate its straight edges while it is being fed or forwarded to the cooling devices, and while it is being cooled by such devices and, furthermore, the construction will be such that the plate will be brought into cooling relation with the cooling medium by a rotary movement, such movement effecting a considerable saving in the size 120 of the machine, which in many instances is a feature of practical importance.

The cooling mechanism, furthermore, will 125 preferably be so constructed and operated that a dwell may be provided while the plate 130

is being cooled to effect a more thorough cooling of the plate and to permit the forwarding of a second plate to the cooling devices while the first one is being cooled. Furthermore, preferably the cooling mechanism will be such as to cool the plate on both the inside and outside.

A cooling mechanism for effecting these results is illustrated in combination with the 10 finishing mechanism hereinbefore described. It will be understood, that if desired, this cooler may be used alone or in combination with other types of finishing mechanism. Where, however, the cooler is used with a 15 finisher to which and from which the plate is forwarded supported at points intermediate its edges, the cooler will be provided with supports coöperating with the supports in the finisher to receive the plate and support it intermediate its straight edges.

In the particular construction illustrated, there is provided a cooling bath which may be of various kinds, but which is shown in the form of a tank 65, which is supplied with 25 a cooling fluid, as water, through an inlet pipe 66, an escape pipe 67 being provided for determining the height of the water level in the tank. The plate to be cooled is brought into cooling relation with this bath 30 by a rotary carrier, and in the best constructions, this rotary carrier is capacitated to carry two plates around and, furthermore, is driven so that there is a dwell or stop during the rotation of the carrier so that 35 while one plate is being fed on to the carrier, a plate previously fed thereto is stopped in the tank.

As the carrier is capacitated to carry two plates around, and as it is necessary for the 40 water to be of sufficient depth to cover the plate, it is desirable to provide a tank construction whereby the water is kept out of the carrier bearings and the adjacent parts of the finishing mechanism, and a construction 45 for effecting this is provided by the present invention. As illustrated, the carrier comprises a pair of spaced heads 68, 69, formed preferably integrally with a hollow hub 70, one end of which is closed, as indicated at 71. This hub is supported by a shaft 72, which at its inner end (see Fig. 7) is provided with a reduced portion 73 which takes bearing in the knife bar 8 of the finisher, before referred to, and is held in position 50 against rotation by pins 74. The shaft is provided with a collar 75 having a cut-away portion 76 to form a shoulder and secured to the hub in any suitable manner to rotate therewith is a driving sprocket 77, 55 this driving sprocket rotating about the collar and having a shoulder 78 taking against the shoulder of the collar 75 and acting to prevent end play of the parts. The hub is, also, provided with a groove 79 in 60 which takes a washer plate or ring 80 se-

cured to the inner end wall 81 of the tank 65. With this construction the water in the tank is effectively prevented from entering the bearings of the carrier and the carrier is held in proper endwise relation with the 70 finisher.

The carrier is provided with means for supporting a plate intermediate its straight edges while the plate is fed on to the carrier and while it is being rotated thereby. 75 In the particular construction illustrated, there are provided (see Fig. 8) a plurality of bars or rods 82, four such bars or rods being provided on each side of the carrier. Means are also provided on the carrier for 80 supporting a plate when it is in reverse position due to the rotation of the carrier. These means are also of such character as to support the plate intermediate its straight edges and may be of any suitable character, 85 as for instance, a pair of rubber covered bars or pipes 83 surrounding the outer periphery of the carrier and supported in frames 83' extending from the heads as shown in Fig. 8.

In the best constructions, means are provided for drying the plate after it has been cooled and preferably on both sides and as the plate leaves the carrier. While this may be accomplished in various ways, in the particular construction illustrated, there is provided an air pipe 84 having upper and lower branches 85, 86, between which the plate passes as it is removed from the carrier, these pipes being supplied with air from any 100 suitable source, not shown, and acting to dry the outside and inside of the plate. From the carrier the plate may be delivered to any suitable delivery, as for instance, a standard indicated at 87.

The cooling carrier may be rotated in any suitable manner. Where it is employed in combination with a finisher, it is preferably driven from the finisher and in time therewith. While the specific mechanism for 110 driving the carrier may be somewhat varied, in the particular construction illustrated, the carrier is driven from the finisher shell 9, before referred to. As shown, there is provided a sleeve 88 suitably supported in the machine frame, which forms a bearing for a short shaft 89. This short shaft has at one end a gear 90, the teeth of which are cut to engage with the worm wheel on the shell 9, before referred to. The short shaft 89 on 120 its other end carries a sprocket 91, and from this sprocket runs a chain 92 over the sprocket 77 on the carrier hub before referred to, through which the carrier hub is rotated. As shown in the drawing, the gears 125 90 and the sprockets 77 and 91 are so proportioned that the cooling carrier is given a half revolution to one full revolution of the finishing cylinder stopping when the finishing cylinder stops, so that a plate on the 130

cooling carrier is held in the bath while another plate is being forwarded to the cooling carrier.

Any suitable mechanism for driving the machine may be employed. As shown, there is a main driving shaft 93 (see Fig. 3) driven in any suitable manner as from a pulley 94. This shaft (see Fig. 1) carries a sprocket 95 from which through a chain 96 the shaft 43, before referred to, is driven.

If desired, cutters may be employed for trimming the ends of the plate as the plate revolves in the carrier. These cutters are indicated in dotted lines in Fig. 3, and marked 97, and are carried on a short shaft 98, driven from a gear 99 on the driving shaft 93. The shaft 15, before referred to, which carries the sector driving worm 20 is or may be driven from shaft 93 by a belt 20, shown in dotted lines in Fig. 1. If desired, high speed cutters 101 (see Fig. 5) may be mounted on this shaft and driven thereby for trimming the straight edges of the plate.

25 By the construction shown and described, a very efficient cooling device has been provided and one which cools the plate without distortion and with great rapidity. Furthermore, owing to the provision of the rotary cooling devices the construction occupies less space than otherwise would be the case. While the cooler has been shown and described with a specific form of finisher, it will be understood that the cooler may be 30 used with other types of finisher than that shown, and that the cooler furthermore may be varied as to its specific construction, and the invention is not to be limited either to the precise type of finisher shown or to the 35 precise construction of cooler.

40 What is claimed is:

1. The combination of a cooling bath, means for forwarding a plate, a rotary carrier, means for holding a plate on the carrier 45 between its straight edges, and means for rotating the carrier to dip the plate in the bath.

2. The combination of means for forwarding a plate, a cooling bath, a rotary carrier 50 capacitated to carry two plates around, means for holding two plates on the carrier between their straight edges, and means for rotating the carrier to dip the plates in the bath.

55 3. The combination of means for forwarding a plate, a cooling bath, a rotary carrier in the bath capacitated to carry two plates around, means for holding two plates on the carrier between their straight edges, and 60 means for rotating the carrier to dip the plates in the bath and for stopping the carrier to hold one plate in the bath while another plate is being forwarded to the carrier.

65 4. The combination of means for forward-

ing a plate supported between its straight edges, a cooling bath, a rotary carrier in the bath to which the plate is forwarded, means for holding a plate on the carrier between its straight edges, and means for rotating the 70 carrier to dip the plate in the bath.

5. The combination of means for forwarding a plate supported between its straight edges, a cooling bath, a rotary carrier in the bath capacitated to carry two plates around, 75 means for holding two plates on the carrier between their straight edges, and means for rotating the carrier to dip the plates in the bath.

6. The combination of means for forwarding a plate supported between its straight edges, a cooling bath, a rotary carrier in the bath capacitated to carry two plates around, means for holding two plates on the carrier between their straight edges, and means for 80 rotating the carrier to dip the plates successively in the bath and for stopping the carrier to hold one plate in the bath while another plate is being forwarded to the carrier.

7. The combination of a tank, a carrier 90 mounted to move in the tank, means on the carrier for supporting a plate between its straight edges, and means for driving the carrier to dip a plate in the tank. 95

8. The combination of a tank, a rotary carrier in the tank, capacitated to carry two plates around, means on each half of the carrier for supporting the plates between their straight edges, and means for driving 100 the carrier.

9. The combination of a tank, a carrier mounted to rotate in the tank, bars on the carrier arranged to support a plate between its straight edges, and means for driving 105 the carrier.

10. The combination of a tank, a carrier mounted to rotate in the tank, bars on the carrier arranged to support a plate between its straight edges, means for driving the 110 carrier, and means for holding a plate on the carrier as it is rotated.

11. The combination of a tank, a rotary carrier in the tank, bars arranged to support a plate between its straight edges, 115 holders spaced from the supporting bars arranged about the periphery of the carrier for holding the plate thereon when the carrier is rotated, and means for driving the carrier.

12. The combination of a tank, a rotary carrier mounted in the tank, means for supporting a plate on the carrier between its straight edges, means for driving the carrier, means for forwarding a plate to the 125 carrier and removing it therefrom, and means for drying a plate as it is removed from the carrier.

13. The combination of a finishing mechanism, a cooling bath arranged adjacent 130

thereto, means for forwarding a plate through the finishing mechanism supported between its straight edges, and means for bringing the plate into cooling relation with the bath while supported between its straight edges.

14. The combination of a finishing mechanism, means for forwarding a plate through the finishing mechanism supported between its straight edges, a cooling bath, a rotary carrier to which the plate is forwarded from the finishing mechanism, means for supporting a plate between its straight edges on the carrier, and means for rotating the carrier to bring the plate into cooling relation with the bath.

15. The combination of a finishing mechanism, supports extending through the finishing mechanism arranged to support a plate between its straight edges, a cooling bath adjacent the finisher, a rotary carrier, supports on the carrier arranged to support a plate between its straight edges, means for forwarding a plate through the finisher to the carrier, and means for rotating the carrier to bring a plate into cooling relation with the bath.

16. The combination of a finishing mechanism, means for forwarding a plate through the finishing mechanism supported between its straight edges, a cooling bath arranged adjacent the finisher, a rotary carrier to which the plate is forwarded from the finishing mechanism, means on the carrier for supporting a plate between its straight edges, and means for intermittently rotating the carrier.

17. The combination of a cooling bath, a carrier having means for supporting a plate between its straight edges, and means for effecting a relative movement of the bath and the carrier to cool the plate.

18. The combination of a finishing mechanism, a cooling bath adjacent thereto, means for forwarding a plate through the finishing mechanism supported between its straight edges, means for bringing the plate into cooling relation with the bath while supported between its straight edges, and means for delivering the plate from the bath.

19. The combination of a finishing mechanism, a cooling bath, means for forwarding a plate through the finishing mechanism supported between its straight edges, a carrier to which the plate is forwarded capacitated to carry two plates around, means for delivering a plate from the carrier and means for moving the carrier to bring a plate into cooling relation with the bath and for stopping the carrier while a plate is delivered therefrom and another plate forwarded thereto.

20. The combination of a finishing mechanism, a cooling bath adjacent thereto, a carrier having means for supporting a plate

between its straight edges, means for forwarding a plate from the finishing means to the carrier while supported between its straight edges, and means for effecting a relative movement of the carrier and the bath.

21. The combination of a cooling bath, a carrier having means for supporting a plate between its straight edges and means for rotating the carrier in the bath to wet both faces of a plate.

22. The combination of a finishing mechanism, a cooling bath arranged beyond the finishing mechanism, a rotary carrier, means for forwarding a plate from the finishing mechanism supported between its straight edges to the rotary carrier, and means for rotating the carrier in the bath to cool a plate on both sides.

23. The combination of a finishing mechanism, a cooling bath, a rotary carrier mounted to rotate in the bath and arranged beyond the finishing mechanism, means for driving the finishing mechanism to finish a plate and connections from the finishing mechanism for rotating the carrier when the finishing mechanism is driven.

24. The combination of a finishing cylinder, a rotary carrier, a cooling bath in which the carrier rotates, means for intermittently driving the finishing cylinder to finish a plate and connections from the cylinder for driving the carrier and causing it to partake of the intermittent movement of the cylinder.

25. The combination of a finishing cylinder, a rotary carrier, a cooling bath in which the carrier rotates, means for intermittently driving the cylinder to finish a plate, means for forwarding a plate into the cylinder and from the cylinder to the carrier, and connections for driving the carrier while the cylinder is driven, and stopping the carrier while a plate is being forwarded to the cylinder.

26. The combination of a rotary finishing mechanism, a rotary carrier, a cooling bath in which the carrier rotates, means for intermittently driving the finishing mechanism to finish a plate and connections from the finishing mechanism for giving the carrier a half revolution while the finishing mechanism makes a whole revolution.

27. The combination of a cooling bath, a carrier having means for supporting a plate between its straight edges, and means for rotating the carrier to effect the cooling of a plate by the bath.

28. The combination of a cooling bath, a carrier having means for supporting a plurality of plates between their straight edges, and means for rotating the carrier to effect the cooling of the plates by the bath.

29. The combination of a cooling bath, a carrier having means for supporting two

plates between their straight edges, and means for intermittently rotating the carrier to effect the successive cooling of the plates by the bath.

- 5 30. The combination of a cooling bath, a carrier having means for supporting a plate between its straight edges, and means for effecting a relative movement of the bath and carrier to wet a plate on both sides.
- 10 31. The combination of a cooling bath, a carrier having means for supporting a plate between its straight edges and means for

rotating the carrier to cause both sides of a plate to be wet by the bath.

32. The combination of a tank, a rotary 15 carrier in the tank having plate holding devices, and means for driving the carrier to submerge a plate in the tank.

In testimony whereof I have hereunto set my hand.

OSCAR ROESEN.
